UNITED STATES PATENT OFFICE.

RICHARD EDWARD WATTS, OF STAMFORD, ENGLAND, ASSIGNOR OF ONE-HALF TO
JOHN HOBKIRK, OF STAMFORD, ENGLAND.

BRASS WIND MUSICAL INSTRUMENT.

1,148,417.

Specification of Letters Patent.

Patented July 27, 1915.

Application filed February 3, 1914. Serial No. 816,252.

To all whom it may concern:

Be it known that I, RICHARD EDWARD WATTS, a subject of the King of Great Britain, residing at Stamford, in the county 5 of Lincoln, England, have invented new and useful Improvements in Brass Wind Musical Instruments, of which the following is a specification.

In an ordinary brass wind musical instrument having the usual three piston valves there is one conduit or air passage through the valves, and each of the valves is adapted, when depressed to connect with this conduit a suitable loop tube. It is 10 well known that when two or three valves are depressed together that the sum of the lengths of the loop tubes in use is too short to produce the required note accurately in tune. Various devices have been proposed 15 to overcome this defect, but to the best of my belief none of these are correct for all the seven positions of the valves in a three valved instrument.

In my improved instrument the tubing 20 in use with each of the seven positions is of the correct length to produce the notes corresponding to these positions perfectly in tune to the equal temperament scale, except of course those harmonics which are well 25 known to be slightly at variance with that temperament.

In my improved instrument I provide 30 three conduits or air passages through the valves, each conduit being connected to 35 tubing of suitable length to produce the notes of one position. Each conduit is provided with a loop tube or loop tubes, adapted to be thrown into connection with it by the depressing of the appropriate valve or 40 valves, thereby lengthening it accurately to produce the required note.

My invention is illustrated in the accompanying drawings, in which:

Figure 1 is a diagram illustrating one 45 method of carrying out my invention. Fig. 2 is a sectional elevation of the casings and valves used to carry the method illustrated in Fig. 1 into effect, and is suitable for a saxhorn. Fig. 3 is a plan of the parts 50 shown in Fig. 2. Fig. 4 is an end elevation of the same. Fig. 5 is a diagram illustrating a modification of my invention. Fig. 6 is a sectional elevation of the casings and valves used to carry this modified form of 55 my invention into effect. Fig. 7 is a full

elevation of one side of the valves and casings of such modification showing the arrangement of connections and valve tubing. Fig. 8 is a full elevation showing the reverse side of the above, and Fig. 9 is a plan 60 of the same. Fig. 10 is a diagram representing another modification of Fig. 1.

In all these drawings the reference letter for the first valve is *a*, for the second *b*, and for the third *c*. The connections between 65 the valve casings are referred to by the letters *d*, *e*, *g*, *h* with the addition of an index numeral. The ports in the valves are marked with the letters *a*, *b*, *c* and *x*, *y*, *z* with the addition of an index numeral. The 70 inlet tube from the mouthpiece is marked *m*, and the outlet tube to the bell of the instrument is marked *o*. The loop tubes, carrying tuning slides are all marked with the letter *f*, the one in use to produce the 75 open notes of the instrument being distinguished by the index numeral "0"—thus *f*⁰. The tube used to lower the pitch one semitone is designated *f*¹, 2 semitones *f*², 3 semitones *f*³, and so on to *f*⁶.

In my invention the air conduit or passage for either the open notes or the valve notes is generally through all the valves on the outward journey and back through the valves on the return journey. In some cases 85 however one or more of these passages passes around one or two of the valves either on the outward journey or on the return journey.

In the diagram Fig. 1 the valves are 90 shown in two groups, the one group *a*, *b*, *c* representing the outward passage from the mouthpiece, and the second group *c*, *b*, *a* representing the return passage to the bell of the instrument. Between the two groups 95 of valves a series of loop tubes of varying lengths is arranged indicated by letters *f*⁰, *f*¹, *f*², *f*³, *f*⁴, *f*⁵, *f*⁶. There are two air passages leading from and returning to the valve *a*, which in this arrangement is the 100 first valve the air enters from the mouthpiece. One of these passages indicated by the line *a*⁰, *d*⁰, *b*⁰, *e*⁰, *c*⁰, loop tube *f*⁰, *x*⁰, *g*⁰, *y*⁰, *h*⁰, *z*⁰, is in use when all the valves are up, and the other indicated by the line *a*², *d*², *b*², *e*², *c*², loop tube *f*², *x*², *g*², *y*², *h*², *z*², is in use when valve *a* is depressed. The first 105 one gives the open note of the instrument and the second one lowers the pitch of the instrument 2 semitones. In this descrip- 110

tion, the valve that the air first enters from the mouthpiece will be referred to as the first valve.

The air may enter first either the valve 5 which is commonly called the first valve or the valve which is commonly called the third valve.

- In addition to the two air passages just referred to there are two other air passages, 16 the one indicated by the line b' , e' , c' loop tube f' , x' , g' , y' being in use when the valve b is depressed alone and lowering the pitch of the instrument one semitone, and the other indicated by the line b^3 loop tube 15 f^3 , y^3 which is in use when the valve b is depressed together with valve a and lowers the pitch of the instrument 3 semitones. Valve c when depressed alone cuts out the open loop tube f^0 and directs the air column 20 through c^6 loop tube f^6 and x^6 , the loop tube f^6 being of correct length to lower the pitch of the instrument 6 semitones. When valve c is depressed along with valve b , valve a being up, it cuts out loop tube f' and directs 25 the air column through c^4 , f^4 , x^4 , the loop tube f^4 serving to lower the pitch 4 semitones, and when valve c is depressed with valve a down and valve b up it cuts out loop tube f^2 and directs the air through c^5 , f^5 , x^5 30 lowering the pitch 5 semitones.

- Figs. 2, 3 and 4 are marked with the same letters and index numbers as Fig. 1, but in Fig. 2 when a valve port makes two connections, one when the valve is normal and one 35 when the valve is depressed, the port is lettered with the letterings appropriate to each connection. The first valve is provided with four ports z^0 , z^2 , a^0 , a^2 , and the first and second valve casings are connected by 4 short 40 tubes h^0 , h^2 , d^0 , d^2 . The second valve has six ports y^0 (y' and y^2), y^3 , b^0 (b' and b^2), b^3 , and the connection between the second and third valve casings are marked g^0 , g' , g^2 , e^0 , e' , e^2 . The ports in the third piston are 45 marked x^0 (x' and x^6), $(x^4$ and x^2), $(x^5$ and c^6), $(c^4$ and c^2) and c^5 , and these ports, as shown in the plan, deflect the air alternately to the right and to the left. Moreover these ports are spaced equidistantly along the axis of the valve. The connections, or loops, are marked f^0 , f' , f^2 , f^3 , f^4 , f^5 and f^6 . With all the valves up the air enters at m and passes through ports and connections marked a^0 , d^0 , b^0 , e^0 , c^6 , through 55 the loop or connection f^0 and returns to the outlet o through x^0 , g^0 , y^0 , h^0 , z^0 . With the first valve down air enters through ports and connections a^2 , d^2 , b^2 , e^2 , c^2 through loop 60 f^2 returning to the outlet o through x^2 , g^2 , y^2 , h^2 , z^2 . With the second valve down air enters through ports and connections a^0 , d^0 , b^0 , e^0 , c^6 through loop f^0 returning through x^0 , g^0 , y^0 , h^0 , z^0 . With the 1/2 valves down air enters through a^2 , d^2 , b^3 loop f^3 returning 65 through y^3 , h^2 , z^2 . The third valve deflects

the air alternately to right and to left. The air which enters f^0 when the third valve is up is deflected into f^6 when the third valve is depressed, and that in f' when the 3rd. valve is up is deflected into f^4 when the 3rd. valve is depressed, that in f^2 with the 3rd. valve up into f^5 when it is down. These are the inlet courses into the loop tubes, the outlet courses are similar, as will be seen. In this arrangement the 1/2/3 combination *i. e.*, 70 first, second and third valves depressed produces the same effect as the 1/2 combination *i. e.*, first and second valves depressed and third valve up. The loops or connections f' , f^2 , f^3 , f^4 , f^5 , f^6 are each fitted with a tuning 80 slide, the tuning slide for f^0 being beyond the valve system.

I have shown the air inlet and outlet tubes on the first valve casing and the loop tubes on the third valve casing, but it is obvious 85 that this arrangement can be reversed. The loop tube f^3 short-circuits the valve c in order to avoid using an inordinately long third piston. It will be seen that the depressing of the valves a , b and c together produces the same effect as depressing only a and b , the air in both cases passing through loop tube f^3 . The valve c , *i. e.* the 3rd. valve, is depressed alone to lower the pitch 6 semitones, not the three valves a , b , and c together as is usual. 90

I sometimes as shown in Fig. 10 arrange the air passage a^0 , d^0 , b^0 , e^0 , c^0 , loop tube f^0 , x^0 , g^0 , y^0 , h^0 , z^0 to miss or pass around the valve c instead of arranging the air passage b^3 loop tube f^3 , y^3 to miss or pass around this valve, in which case the fingering of the instrument is the same as is usual with the exception that depressing the 3rd. valve alone produces no effect. In this arrangement the operations are as follows:—When all the valves are up the air enters at m and passes through ports and connections marked a^0 , d^0 , b^0 through the loop or connection f^0 and returns to the outlet o through ports y^0 , h^0 , z^0 . With the first valve down air enters through a^2 , d^2 , b^2 , c^2 , e^2 through loop or connection f^2 returning to outlet o through x^2 , g^2 , y^2 , h^2 , z^2 . With the second valve down air enters through a^0 , d^0 , b^0 , e^0 , c^6 through loop or connection f' , returning through x^0 , g^0 , y^0 , h^0 , z^0 . With the 1/2 valves down air enters through a^2 , d^2 , b^3 , e^3 , c^3 through loop or connection f^3 returning through x^3 , g^3 , y^3 , h^2 , z^2 . The third valve deflects the air alternately to right and to left. The air which enters f' when the 3rd. valve is up is deflected into f^4 when the 3rd. valve is depressed, and that in f^2 when the third valve is up is deflected into f^5 when the 3rd. valve is depressed, f^3 with the 3rd. up into f^6 when it is down. These are the inlet courses, the outlet courses are similar, as will be seen. 115

It will be understood from the foregoing 120

- description and by studying Fig. 1 that the loop tubes f^0 to f^6 are independent tubes and each is used to produce the notes appropriate to one position only.
- 5 I will now describe the modification shown in Figs. 5 to 9. In this modification the length of the valves is much reduced and less tubing is required in its construction.
- 10 Referring to the diagram Fig. 5. In this arrangement the air from the mouthpiece is led first to valve c from which the outlet tube also leads to the bell of the instrument. The air conduit or passage producing the 15 open note of the instrument when all the valves are up is indicated by the line $c^0, e^0, b^0, d^0, a^0, h^0, y^0, g^0, x^0$. The air passage $c^3, e^3, b^3, d^3, ax^3, fx^3, x^3$, in use when the valve c is depressed is so much longer than the open 20 air passages in use when all the valves are up as to lower the pitch of the instrument very nearly 3 semitones; the reason for the qualification "very nearly" will appear later. In this arrangement only the air 25 passage indicated by the line b', d', a' loop tube f', y', g^0, x^0 , is in use when the valve b is depressed either alone or with valve a . In this air passage is arranged the loop tube f' which makes it of correct length to lower 30 the pitch one semitone when valve b is depressed alone. When valve a is depressed alone it throws into the open air passage c^0, e^0, b^0 and so on, the loop tube f^2 in the ordinary and well understood manner, thus 35 correctly lowering the pitch of the instrument 2 semitones. When the valve a is depressed together with valve b it throws into the air passage b', d', a', f', y' the loop tube f^3 which correctly lengthens said air passage 40 so as to lower the pitch 3 semitones. When the valve b is depressed together with valve c it throws into the air passage marked c^3, e^3, b^3, d^3 and so on the loop tube f^4 which lengthens this air passage sufficiently to 45 lower the pitch 4 semitones in all; similarly when valve a is depressed with valve c the loop tube f^5 is thrown into air passage lowering the pitch 5 semitones in all. To lower 50 the pitch 6 semitones the valves a and b are both depressed with valve c . It will be obvious that if the loop tube fx^3 is of correct length to lower the pitch 3 semitones and the loop tubes f^4 and f^5 are each of correct length to lower the pitch respectively 4 and 55 5 semitones when used in connection with this tube (fx^3) with valve c depressed that if both are used together with valve c the length of tubing in use will be too short to produce seventh position notes accurately in 60 tune. I remedy this defect in the following manner. As the loop tube fx^3 used alone is only an alternative for the tubes f^3, f' in use with the valves a and b depressed, I make this tube rather short and the loop 65 tubes f^4 and f^5 proportionately long, the cor- rect length being indicated in the following simultaneous equations:— $fx^3 + f^4$ = correct length to lower pitch 4 semitones, $fx^3 + f^5$ = correct length to lower pitch 5 semitones, $fx^3 + f^4 + f^5$ = correct length to lower pitch 6 semitones. These lengths provide correct 7th. position or $1/2/3$ notes—i. e., notes produced when the first, second and third valves are simultaneously depressed—at the expense of slightly shortening the alternative 3 semitone notes made with the valve c alone and only used in rapid passages to simplify the fingering.
- Referring to Figs. 6, 7, 8 and 9 the valve c has four ports x^0, x^3, c^0, c^3 and the casings of the valves c and b are connected by three short tubes g^0, e^0, c^3 . The valve b has five ports y^0 (y' and b^0) (b' and b^3) b^4 and y^4 and the casings of the valves b and a are connected by 4 short tubes h^0, d^0, d^3, d^4 . The valve a has seven ports a^0, z^2 (a' and a^2) z^3, a^3 and ax^3, z^5 and a^5 . The tuning loops are marked f', f^2, f^3, f^4, f^5 and fx^3 . With all the valves up, the air enters at m and passes through loops and connections $c^0, e^0, b^0, d^0, a^0, h^0, y^0, g^0$, and x^0 to the outlet o . With the first valve a down air passes through ports and connections c^0, e^0, b^0, d^0, a^2 , loop tube f^2 then through z^2, h^0, y^0, g^0 and x^0 , to o . With valve b down, the air passes through c^0, e^0, b', d', a' loop tube f' through y', g^0 and x^0 to o . With valves a and b depressed the air passes through ports and connections c^0, e^0, b', d', a^3 loop tube f^3 through z^3 loop f' , through y', g^0, x^0 to o . With valve c depressed, the air passes through c^3, e^3, b^3, d^3, ax^3 loop tube fx^3 missing valve b through port x^3 to o . With valves c and a down, passage is through c^3, e^3, b^3, d^3, a^3 loop tube f^5 , through z^5 loop fx^3 through port x^3 to o . With valves c and b down, passage is through c^3, e^3, b^4 loop f^4 through y^4, d^3, ax^3 loop fx^3 through x^3 to o . With all valves down, passage is through c^3, e^3, b^4 loop f^4 through y^4, d^3, a loop f^5 , through z^3 loop fx^3 through x^3 to o .
- What I claim is:
1. A brass wind musical instrument with three piston valves, having in combination with the valves two independent air passages controlled by one of the valves, and a third air passage which by depressing another of the valves is substituted for one of said air passages.
  2. A brass wind musical instrument having the usual three piston valves and provided with two independent air passages or conduits through the valves namely, $c^0, e^0, b^0, d^0, a^0, h^0, y^0, g^0, x^0$, and $c^3, e^3, b^3, d^3, ax^3, fx^3, x^3$, one in use when the first valve is up and the other in use when this valve is depressed, in combination with ports and connections whereby the depressing of the second valve causes a portion of one of these air passages namely, b^0, d^0, a^0, h^0, y^0 , to be cut

out and replaced by an independent air passage b' , d' , a' , f' , y' .

3. A brass wind musical instrument with three piston valves, having two independent air passages controlled by the first valve and an independent third air passage controlled by the second valve, said third air passage passing once only through the third valve.

10 4. A brass wind musical instrument with three piston valves, having two independent air passages controlled by one of the valves, a third air passage controlled by another of the valves, and an ordinary loop f^3 on the 15 remaining valve which can be added to said third air passage by the depression of the said remaining valve.

5. A brass wind musical instrument with three piston valves, having two independent 20 air passages controlled by the first valve, a third air passage controlled by the second

valve, a loop on the third valve, which loop can be added to the said third air passage by depressing the said third valve, a loop on the second valve which can, by depressing 25 the second valve, be added to one of the air passages controlled by the first valve, and two other loops on said third valve which can, by depressing the third valve, be added respectively to the two air passages controlled by the first valve.

6. A brass wind musical instrument with three piston valves having two independent air passages passing through the three valves and controlled by the first valve, a third air passage controlled by the second valve, and a loop controlled by the second valve.

RICHARD EDWARD WATTS.
